UNITED STATES PATENT OFFICE.

S. BROWNLEE FISHER, OF PITTSBURG, PENNSYLVANIA.

CROSS-SECTION ROD.

SPECIFICATION forming part of Letters Patent No. 255,778, dated April 4, 1882.

Application filed June 20, 1881. (Model.)

To all whom it may concern:

Be it known that I, S. BROWNLEE FISHER, a citizen of the United States, residing at Pittsburgh, in the county of Allegheny and State of Pennsylvania, have invented a new and useful 5 Cross-Section Rod, of which the following is a specification.

My invention consists of two graduated rods connected together by a spindle-joint, so that 10 they are capable of revolving about each other freely in one plane, and also so connected to each other that their relative positions can be changed and adjusted by sliding movements in the directions of their axes. When in use 15 the axis of one rod is designed to be vertical and adjusted therein by means of a level-bulb or plumb-line attached to the rod. The axis of the other rod is intended to be in the horizontal plane when in action and adjusted 20 therein by a level or plumb.

The object of my invention is to provide an 25 instrument for taking cross-sections of the ground in such places and circumstances as render the use of the engineer's level in the ordinary way slow and inconvenient, as on very 30 steep, rough, broken, rocky, or bushy slopes and hillsides, on the surfaces or slopes of cuttings and embankments, &c., and in such circumstances to insure accurate horizontal as well as vertical measurements. I attain these 35 objects by the mechanism illustrated in the accompanying drawings, in which—

Figure 1 is a vertical elevation of the entire 40 instrument, showing its position in use. Fig. 2 is an elevation of the parts about the joint and the ends, with the section 1 2 and 3 4 through the spindle-joint. Fig. 3 is a plan corresponding to Fig. 2, in elevation. Fig. 4 is an isometrical drawing of parts about the joint.

Similar letters refer to similar parts throughout the several views.

A A' is the vertical rod, shod with iron or brass at the lower end, A', to prevent wear, provided with a level-bulb at I, and graduated 45 from bottom to top. It is encircled by a strap or stirrup, P, attached to the spindle-socket T. The stirrup and rod are to be clamped together at any point by any suitable means—as, for example, by a wedge, W, as shown in the drawings. This wedge, when out of reach of the hand, may be tightened by pressing a stick or

small rod against its base. It may be loosened by pulling a string attached to it, being prevented from dropping out by a small cross-bar attached to the upper end.

B B' is the horizontal rod, also shod with iron or brass at the end B, which comes in contact with the ground, provided with a level at H, and graduated from B toward B'. It is embraced by the strap or stirrup F, attached 60 to the spindle T, which stirrup is left open on the graduated side of the rod to admit of the figures and graduations being more plainly seen. The rod is clamped to this stirrup—as, for instance, by an eccentric-disk, C—as shown 65 in the drawings.

The rods A A' and B B' revolve freely about each other by means of the spindle-joint T. By means of this spindle-joint T, which may be located at any convenient point with reference 70 to the straps P and F, they can be readily adjusted at right angles to each other, one in a vertical position, the other horizontal, and folded up for transportation when out of use.

The stirrups have attached to them graduated limbs E and D. The zero of the horizontal graduated limb E coincides with the line on which graduations are made on A A'. The zero of the vertical graduated limb D coincides with the lower edge of the rod B B'. 80 These limbs are shown on drawings as graduated to hundredths of a foot and the rods as graduated to tenths, thus reading to hundredths. If desired, the rods may be graduated to hundredths and the limbs graduated as 85 verniers, thus reading to thousands.

To use this instrument, the rod A A' is placed upon a level peg in the center line, the elevation of which has been previously obtained by the engineer's level in the usual 90 manner. When the cross-section of the slopes of cuttings and embankments alongside a railroad already built is to be taken (and for this purpose it is thought this instrument will be very convenient, accurate, and expeditious in 95 operation) the top of rail, the elevation of which has previously been obtained, is taken as the initial point of the cross-section. The rod A A' is then held vertically over the peg or point, which will be indicated by the level 100 or plumb attached to it. The rod B B' is then adjusted to any point in the cross-section

which is to be taken, as B'' , Fig. 1, being made level, which will be indicated by the level H attached to it. The vertical distance of this point B'' from the point A' is now read on the 5 vertical rod $A A'$ and its horizontal distance on the rod $B B'$. Both these distances are now recorded in the note-book. The next point is then taken, and so on until the turning-point is reached. At this latter point, for accurate 10 work, a peg should be driven in the ground at B and the position of the end of the rod $B B'$ marked on it. When the instrument is moved forward the graduated line of $A A'$ is placed directly over this mark. When the vertical 15 and horizontal distances of the turning-point are obtained and recorded the instrument is moved forward, the vertical rod placed over the turning-point, and the operations repeated until another turning-point is reached, &c., as 20 far as it is desired to extend the cross-section. The process, as here described, takes the cross-section as going up hill. In going down hill the peg is driven for the vertical rod $A A'$. The process in going down hill is evidently 25 very similar to that in going up hill. It will be found very convenient in the future plotting of the work to make the turning-points

come at the end of the horizontal or vertical rod, or at even ten feet.

I am aware that disconnected rods have been 30 sometimes used by engineers in taking cross-sections. I am not aware that the graduated rods have ever been combined so as to make a single instrument and attain the objects above described. 35

What I therefore claim as my invention is—

The combination of the vertical graduated rod $A A'$, provided with a level-bulb, L , with the horizontal graduated or measuring rod $B B'$, provided with a level-bulb, H , by means of 40 the stirrup P , provided with a graduated limb, D , the stirrup P , sliding along and capable of being clamped to the rod $A A'$, and the stirrup F , provided with a graduated limb, E , sliding along and capable of being clamped to 45 the rod $B B'$, the two stirrups P and E being connected together by the spindle-joint T , so as to form a single instrument for the purpose of taking cross-sections on rough, rocky, steep, and bushy ground, as herein set forth.

S. BROWNLEE FISHER.
